UNITED STATES PATENT OFFICE.

SIDNEY R. BLAKELY, OF JAMAICA PLAIN, MASSACHUSETTS.

BOOT AND SHOE AND METHOD OF MAKING THE SAME.

Application filed November 21, 1927. Serial No. 234,728.

My present invention relates to boots and shoes, and more particularly to boots or shoes of the McKay type, and includes a novel method of manufacturing same.

5 An important object of the present invention is the production of a McKay shoe in which a heel cushion is applied to the inner heel seat of the shoe, thus necessitating having a portion of the insole free of stitches, 10 nailing, or other securing means, in order to permit the said cushion to be inserted after the shoe is otherwise completed.

A further and important object of the said invention is to continue the through and 15 through stitching past the line of the heel breast of the shoe and well into the heel portion, which results in a much stronger, more durable, and longer wearing shoe, since the heel portion of a shoe, particularly at the 20 heel breast, is one of the weak points in a shoe. I am enabled to obtain this desirable result in an insole constructed and arranged to permit the through and through stitching to be continued past the line of the heel breast 25 but without penetrating the said insole beyond said line leaving the rear or heel portion of the insole free to be raised to permit the application or insertion of the heel 30 cushion above referred to. I accomplish this desirable result by slitting or cutting the insole from each side thereof, at a point forward of the heel breast, thus enabling the sides of the insole rearwardly of the 35 said cuts to be upturned at the time of applying the through and through stitching, in order that the said stitching may continue beyond the line of the cuts on the insole and well into the heel portion of the shoe.

A further object of the invention is the 40 provision of an outsole, which is constructed by cutting away the peripheral edge of the said outsole around the heel and inwardly for a predetermined distance. The remaining portion of the heel of the outsole is then beveled, to provide a filler for the hollow shoe-engaging surface of heels to be applied, the outer breast corners of the outsole being cut substantially straight, to afford abutments for the corresponding breast corners 45 of the heel to be applied thereto.

In carrying out my present invention, I first prepare my insole as above briefly ex-

plained, viz., with the slits or cuts formed therein forwardly of the heel breast. I then apply this insole to a last, preferably 55 formed with an accentuated convexity on the heel seat portion thereof. The insole is first temporarily secured to the last by usual lasting tacks and then a heel clinching plate is temporarily affixed over the insole at the 60 heel portion. Over the insole and clinching plate is then applied a heel and shank piece, preferably of leather or the like, which is permanently secured to the insole at the shank portion, and temporarily secured at 65 the heel portion. The upper materials are then lasted over the thus assembled insole, clinching plate, and heel and shank piece, and secured thereto by lasting tacks or staples in the usual manner. Then my outsole, al- 70 ready prepared, is applied to the thus as- sembled shoe and temporarily secured thereto. The last and clinching plate are then withdrawn and through and through stitching applied, running completely around the 75 forepart and shank of the shoe and well into the heel portion past the heel breast, the edges of the insole rearwardly of the afore- 80 said cuts being upturned so that the said edges will be free of the said stitching. The heel is then applied, a heel cushion or support inserted between the insole and the heel piece, and the insole turned down and the shoe is then completed.

If desired, I may utilize a metallic or other 85 shank stiffener, applying this to the shoe over the shank and heel piece. Usual shoe bottom filler will also, of course, be utilized.

I believe that a boot or shoe constructed according to the brief description above is 90 novel and have therefore claimed the same broadly herein.

I also believe that the process of man- 95ufacturing these boots or shoes is novel, and the said process is also claimed herein.

I further believe that the combination and arrangement of the insole and the outsole de- 100 scribed herein are novel, and both of these elements are included in the claims in the present application.

The above and further features of the in- 100vention, details, combinations, and advan- tages, will be hereinafter more fully pointed out and claimed.

Referring to the drawings, illustrating a preferred embodiment of the present invention,

Fig. 1 is a perspective view of my novel prepared insole;

Fig. 2 is a side elevation of the said insole and a clinching plate assembled on a last;

Fig. 3 is a perspective view of the heel and shank piece;

Fig. 4 is a side elevation similar to Fig. 2 with the heel and shank piece assembled with the insole and clinching plate;

Fig. 5 is a cross-sectional view on the line 5—5 of Fig. 4, but with the upper materials assembled on the last;

Fig. 6 is a longitudinal sectional view of the shoe assembled on the last with the outsole applied;

Fig. 7 is a perspective view of the shoe with the through and through stitching applied, and illustrating the novel construction of the outsole;

Fig. 8 is a perspective of the inner heel portion of the shoe, illustrating the method of turning up the edges of the insole to permit the through and through stitching to continue past the breast portion;

Fig. 9 is a longitudinal sectional view of the heel portion of the completed shoe; and

Fig. 10 is a cross-sectional view on the line 10—10 of Fig. 9.

Referring now to the drawings for a complete description of the invention, and the preferred method of carrying out the same, Fig. 11 designates my novel insole in which I form a pair of slits or cuts 12, extending inwardly from the sides of the insole and forwardly of the heel breast portion thereof. Thus, the edge 13 may be turned upwardly as a flap, avoiding the through and through stitching when same is applied, and leaving the heel portion 14 of said insole free to be lifted from the heel of the shoe.

This insole is first positioned on a last 15 and temporarily secured thereto by last tacks, such as 16, a clinching plate 17 being positioned over the insole at the heel portion of the shoe and temporarily secured to the last by a tack 19 extending through the aperture 18 in the plate, as well as through the insole.

To the thus assembled insole 11 and clinching plate 17, I apply a shank and heel piece 20, preferably of leather or equivalent material, permanently securing this piece 20 to the insole by staples 21 or the like, and temporarily securing the said piece 20 to the last by tacks 22 and 23, the tack 23 extending through the piece 20, and through the aperture 18 in the clinching plate 17. The tack 23 may take the place, if desired, of the tack 19, it not being essential to utilize both of these tacks, since they will be in approximately the same location.

To the shoe materials as thus far assembled, I then apply the upper materials designated

generally at 24 which are pulled over and fastened in the usual manner, preferably by staples around the forepart and shank, and by nails 25 or other suitable securing devices, the nails 25 being clinched against the plate 17 without penetrating the insole of the shoe, but being secured through the shank and heel piece 20.

The tacks 16, 19, 22 and 23 are then withdrawn and usual shoe bottom filler 26 applied to fill the shoe bottom cavity created by the edges of the lasted upper materials 24. If desired, I may then apply a suitable shank stiffener 27, of metal or other suitable or desirable material extending from a point in the heel of the shoe forwardly along the shank and longitudinal arch portion of the shoe.

My novel outsole 28, already prepared, is then applied to the shoe and temporarily secured thereto by tacks 29. I prepare this outsole by cutting away the peripheral edge of the heel, from the heel breast forwardly, and inwardly for a predetermined distance. The remaining portion 30 of the heel of the outsole is then beveled, as shown at 31, substantially straight edges being left at the outer heel breast corners 32, to provide abutments for the corresponding breast corners of the heel to be later applied.

The last 15 is then withdrawn from the shoe, the clinching plate 17 removed, and through and through stitching 33 is applied, I carrying this stitching past the heel breast and well into the heel of the shoe, as shown at 34, thus providing an extremely strong jointure at this portion of the shoe, which portion has heretofore been the cause of annoyance due to the weakness thereof. In order to continue this stitching past the breast portion and into the heel, while at the same time leaving the insole free of the stitching from the cuts 12 rearwardly, I turn up the flap 13 while the through and through stitching is being applied.

The shoe is now ready for the application of the heel 35, which may be and preferably is in the present instance, formed of wood, with a deeply cupped heel seat engaging surface 36. This heel has a lift 37, and is attached to the shoe, preferably by nails 38 driven into the heel from the inside of the shoe. From an inspection of Fig. 10 it will be seen that the portion 30 of the outsole forms an ideal filler for the cup 36 in the heel 35. The heel portion 14 of the insole, is, of course, raised during the heel nailing operation, the heel nails penetrating the heel and shank piece 20 and outsole 28, being applied at either side of the shank stiffener 27, or through the same if means is provided for such application. Subsequent to the heel nailing and attaching operation, I apply, over the heel and shank piece 20, and under the heel portion 14 of the insole 11, a cushion or heel pad 39, which may be adhered, if de-

sired, to the said heel piece 20. This heel cushion or pad is constructed to fit into the deep cup in the heel formed by the construction of the shoe on a last with an extremely 5 convexed heel surface, and forms a perfect rest for the heel of the wearer. The heel portion 14 of the insole is then lowered into position over the cushion or pad 39, and may be adhered thereto, if desired, or it may be left 10 free, it not being of sufficient length to cause excessive wrinkling or discomfort to the wearer.

It will thus be appreciated that I have devised a novel shoe of the McKay type, as well 15 as a novel method of manufacturing same, and that the insole and outsole described herein are also both novel, and represent distinct steps forward in the art of making McKay boots or shoes.

20 While I have necessarily described my present invention somewhat in detail, it will be appreciated that I may vary the size, shape and arrangement of parts within reasonably wide limits, without departing from the 25 spirit of the invention.

My invention is further described in the form of claims as follows:

1. A McKay shoe comprising an insole, a shank and heel piece under said insole, upper materials, an outsole and heel, said outsole being secured by through and through stitching to said upper materials, shank and heel piece and insole rearwardly to a point forward of the heel breast, and rearwardly 35 from said point to the heel breast to the upper materials and heel and shank piece only, said insole being free of said stitching from said point rearwardly, said stitching, from the heel breast rearwardly for a predetermined 40 distance, uniting the upper materials and shank and heel piece only, and a reduced beveled portion of said outsole acting as a filler for the seat of said heel.

2. The improved method of manufacturing 45 McKay shoes, which comprises providing an insole with a pair of slits extending inwardly from the sides of said insole forwardly of the breast portion, applying said insole to a last, securing a clinching plate over the heel portion of said insole, attaching a shank and heel piece over said plate and insole, lasting upper materials over the insole, clinching plate and shank and heel piece, turning up the edges of said insole 50 rearwardly of said slits, attaching an outsole by through and through stitching continuing beyond the breast of the shoe and for a predetermined distance into the heel, said insole being free of said stitching from said 55 slits rearwardly because of its upturned edges.

3. The improved method of manufacturing 60 McKay shoes, which comprises providing an insole with a pair of slits extending inwardly from the sides of said insole forwardly of the

breast portion, applying said insole to a last, securing a clinching plate over the heel portion of said insole, attaching a shank and heel piece over said plate and insole, lasting upper materials over the insole, clinching plate and shank and heel piece, applying an outsole, withdrawing the last and clinching plate, turning up the edge of said insole rearwardly of said slits, and applying through and through stitching through said outsole, upper materials, heel and shank piece and insole as far as the said slits, and rearwardly from that point through the outsole, upper materials and shank and heel piece.

4. The improved method of manufacturing 65 McKay shoes, which comprises providing an insole with a pair of slits extending inwardly from the sides of said insole forwardly of the breast portion, applying said insole to a last, securing a clinching plate over the heel portion of said insole, attaching a shank and heel piece over said plate and insole, lasting upper materials over the insole, clinching plate and shank and heel piece, applying an 70 outsole, withdrawing the last and clinching plate, turning up the edge of said insole rearwardly of said slits, applying through and through stitching through said outsole, upper materials, heel and shank piece and insole as far as the said slits, and rearwardly from that point through the outsole, upper materials and shank and heel piece.

5. The improved method of manufacturing 75 McKay shoes, which comprises providing an insole with a pair of slits extending inwardly from the sides of said insole forwardly of the breast portion, applying said insole to a last, securing a clinching plate over the heel portion of said insole, attaching a shank and heel piece over said plate and insole, lasting upper materials over the insole, clinching plate and shank and heel piece, providing an 80 outsole, forming the heel of said outsole to act as a filler for the seat of a heel, applying 85 said outsole, withdrawing the last and clinching plate, turning up the edge of said insole rearwardly of said slits, and applying through and through stitching through said outsole, upper materials, heel and shank piece and insole as far as the said slits and rearwardly from that point through the outsole, upper materials and shank and heel piece, and attaching a heel from the inside of the shoe.

6. The improved method of manufacturing 90 McKay shoes, which comprises providing an insole with a pair of slits extending inwardly from the sides of said insole forwardly of the breast portion, applying said insole to a last, securing a clinching plate over the heel portion of said insole, attaching a shank and heel piece over said plate and insole, lasting upper materials over the insole, clinching plate and shank and heel piece, providing an outsole, forming the heel of said outsole to act as a filler for the seat of a heel, applying 95 said outsole, withdrawing the last and clinching plate, turning up the edge of said insole rearwardly of said slits, and applying through and through stitching through said outsole, upper materials, heel and shank piece and insole as far as the said slits and rearwardly from that point through the outsole, upper materials and shank and heel piece, and attaching a heel from the inside of the shoe.

7. The improved method of manufacturing 100 McKay shoes, which comprises providing an insole with a pair of slits extending inwardly from the sides of said insole forwardly of the breast portion, applying said insole to a last, securing a clinching plate over the heel portion of said insole, attaching a shank and heel piece over said plate and insole, lasting upper materials over the insole, clinching plate and shank and heel piece, providing an outsole, cutting away the peripheral edge of the said 105

outsole from the heel breast, rearwardly and inwardly for a predetermined distance, forming heel breast corners on said outsole, applying said outsole, withdrawing the last and clinching plate, turning up the edge of said insole rearwardly of said slits, and applying through and through stitching through said outsole, upper materials, heel and shank piece and insole as far as the said slits and rear-

wardly from that point through the outsole, 10 upper materials and shank and heel piece, and attaching a heel from the inside of the shoe, the breast corners of said heel abutting against said breast corners on said outsole.

In testimony whereof, I have signed my 15 name to this specification.

SIDNEY R. BLAKELY.
